CHARLES L. HEISLER, OF SCHENECTADY, NEW YORK.

DRAW-BAR BUFFER-COUPING FOR LOCOMOTIVES.

1,257,859.

Specification of Letters Patent. Patented Feb. 26, 1918.

Application filed November 15, 1915. Serial No. 61,551.

To all whom it may concern:

Be it known that I, CHARLES L. HEISLER, of Schenectady, in the county of Schenectady and State of New York, have invented a certain new and useful Improvement in Draw-Bar Buffer-Couplings for Locomotives, of which improvement the following is a specification.

My invention relates more particularly to a radial spring cushioned buffer and draw bar coupling adapted to connect a locomotive with its tender, and its objects are to provide an effective and simple buffer member disposed between the frames of a locomotive and its tender in such manner as to prevent the member from being cramped, or wedged, tight by any relative movement of the frames when the locomotive passes over curves, or uneven track; to provide an efficient cushion between the frames; to provide a simple and effective mounting for a safety coupling draw bar and service draw bar; and to provide a simple means for applying initial stress to the spring cushioning buffer thereby permitting an easy insertion and assembling of the draw bars and their related parts.

The improvement claimed is hereinafter fully set forth.

In the accompanying drawings: Figure 1 is a view, the upper half of which is in plan and the lower half in section on the line B B of Fig. 2, illustrating my invention as applied in coupling a locomotive to its tender; Fig. 2, a vertical longitudinal section, on the line A A of Fig. 1, showing, however, a modified form of coupling pin at the right hand end; Fig. 3, a vertical transverse section, the left hand half being taken on the line D D of Fig. 1, and the right hand half on the line E E; Fig. 4, a front view in elevation, of one half of the appliance, the adjoining engine frame being shown in section; Fig. 5, a vertical transverse section, the right hand half being taken on the curved line between 7th and 1st, Fig. 1, and the left hand half on the line G G of the same figure; Fig. 6, a rear or left hand end view, in elevation, of the buffer member which is interposed between the locomotive and tender frames, and Fig. 7, a similar view of a spring cap which is interposed between the buffer member and the tender frame.

My invention is herein exemplified as applied in connection with a locomotive and tender of well known standard forms, the locomotive having a main frame 1, coupled to the tender frame 2, by a service draw bar 3, and the coupling draw bar pins 4 and 5, which are fitted in their respective frames in the usual manner. The service draw bar 3, is provided with draw bar pin slots, 3^a, at its opposite ends, which slots engage in close contact at their outer opposite ends with the pins while fulfilling their well known functions in usual service of transmitting the pull of the locomotive to the tender and any cars that may be coupled thereto. The safety draw bar 6, is of substantially similar construction to the bar 3, except that it is allowed a predetermined amount of longitudinal freedom, by an increase of distance between its slots 6^a, in order to avoid close contact with the draw bar pins, thereby preventing it from coming into action, and being stressed, so long as the service bar is capable of safely transmitting the locomotive's pull. When the service bar 3, is excessively strained under abnormal service conditions, as by a sudden pull; or is lengthened by excessive wear of the slots and pins, then the safety draw bar 6, will safely transmit the locomotive's pull until the service bar can be repaired and again given its proper length, which is a predetermined amount shorter than that of the safety draw bar. This latter bar is preferably coupled by the same draw bar pins that pivotally connect the service bar to the frames. It is disposed in the same vertical longitudinal plane to permit the use of a minimum amount of longitudinal freedom on the pins necessary to compensate for relative frame movement when passing curves, thereby preventing it from being subjected to extremely excessive shocks and suddenly applied stresses, when the service bar is accidentally broken; furthermore, this arrangement avoids the use of two oppositely and adjacently disposed bars, or chains, as commonly applied which require an excessive and unsafe amount of longitudinal freedom to compensate for relative frame movement, thereby merely giving a false sense of security. This seriously objectionable feature is entirely avoided by my improvement.

When desired, the draw bar pins may each be made in two longitudinally adjoining sections, and each section may be supported vertically by independent means, as 5 by using a head 4^b, to support the upper section, and applying the common form of bottom cover plate supports, 4^d and 5^d, which are fastened to the frames by bolts 4^e and 5^e. The use of an undivided pin, 5, 10 is simpler, and is equally safe, since if one end, or section, is sheared, or broken, the other still remains and is positioned by its head 5^b, or bottom cover plate 5^a.

A movable buffer member 7, is interposed between the adjoining ends of the frames 1 and 2. Its rear end terminates in a convexed wear face 7^a, which is preferably formed concentric with the axis of the rear draw bar pin 5, and may be in the form 20 of a convexed or spherical segment. The rear end slidingly abuts, or seats, against a corresponding concaved surface 8, formed in a spring cap 8, which is supported on the tender frame within the housing 2^a. A 25 spring 9, (one or more) is interposed between this spring cap and the frame 2, thereby providing a cushion for the buffer member 7. When the rear wear face 7^a, is of spherical segmental form, it gives the buffer member a predetermined and necessary amount of twisting freedom about its longitudinal horizontal axis, to accommodate any relative twisting movement between the frames which is transmitted thereto when 30 the tender is rolling toward one side and the locomotive toward the opposite side. The front end of the buffer member terminates in a vertically disposed cylindrical segmental concaved wear face 7^e, which is 35 preferably made concentric with the axis of the front draw bar pin 4, which wear face slidingly seats itself against a convexed cylindrical surface 1^a, formed on the locomotive main frame, and likewise made concentric with the axis of the draw bar pin 4. This surface 1^a, and the wear face 7^e, 40 are adapted to slide upon each other both laterally and vertically. The buffer member 7, moves with the tender frame because 45 of being supported thereby within the spring cap, and buffer member, housing 2^a, formed in the frame 2. This housing embraces the buffer member and supports it by the sliding surfaces 2^b and 2^d, formed at the 50 opening 2^c, of the housing. These surfaces permit the buffer member to swing freely horizontally about the rear draw bar pin 5; but prevent vertical movement thereof. This rear draw bar pin projects down- 55 wardly through a slot 7^f, formed in the rear end of the buffer member and is disposed concentrically with the rear wear face 7^a, or 8^a. The slot 7^f, gives considerable longitudinal freedom of motion to the buffer 60 member, with respect to the draw bar pin,

to permit its automatic adjustment for wear on the wear faces, and for cushioning action of the spring 9. Clearance notches 7^g, are formed in the rear wear face of the buffer member for the purpose of permitting its 70 ready removal from between the draw bar pin bosses 5^f, and 5^g, formed in the housing 2^a. An additional draw bar pin boss 2^f, is formed on the frame 2, and preferably integral with the housing, directly below the 75 bosses 5^f and 5^g, for the purpose of supporting the lower end of the draw bar pin 5, and the rear end of the corresponding draw bar 6, disposed under the housing 2^a. In like manner, a draw bar pin boss 4^f, is 80 formed integral with the frame 1, and disposed directly under the intermediate boss 4^g and the upper draw pin boss 4^h, also formed integral with the frame 1, for the purpose of supporting the front ends of the 85 service and safety draw bars and for fastening the draw bar pin 4.

For the purpose of applying initial compression to the cushion springs, the spring cap adjusting bolts 8^b, are attached to the 90 tender frame and pass through bolt lugs 8^d, formed on the cap. By turning the nuts 8^e, the cap can be forced against the spring far enough to permit an easy insertion of the draw bar, buffer member and draw bar pin, 95 when coupling the locomotive to the tender.

I do not wish to limit myself in placing the spring 9 and spring cap 8, on the tender frame; as evidently the arrangement can be reversed, by placing the spring and 100 buffer member on the locomotive frame.

I claim as my invention and desire to secure by Letters Patent:—

1. The combination with a locomotive main frame, of a tender frame, coupling draw 105 pins fastened in said frame; a draw bar longitudinally disposed between the frames and pivotally coupled thereto by the draw pins, a convexed surface supported on one frame, a concaved surface supported on the other 110 frame, and a movable buffer member interposed between the frames and said surfaces and having oppositely disposed convexed and concaved wear faces formed thereon, and adapted to abut against the respective 115 and corresponding concaved and convexed surfaces.

2. The combination with a locomotive main frame, of a tender frame, coupling draw pins fastened in said frames, a draw bar longitudinally disposed between the frames and pivotally coupled thereto by the draw pins, a convexed surface supported on one frame, a concaved surface supported on the other frame, a movable buffer member interposed 120 between the frames and said surfaces and having oppositely disposed convexed and concaved wear faces formed thereon, and adapted to abut against the respective and corresponding concaved and convexed sur- 125 130

faces and cushioning means interposed between said buffer member and one of the frames.

3. The combination with a locomotive main frame, of a tender frame, means for coupling said frames, a movable buffer member interposed between said frames and having oppositely disposed convexed and concaved wear faces, a spring cushion interposed between 10 said buffer and one of the frames, and adjusting means formed on said frame for applying initial stress to the spring to permit an easy insertion and assembly of the coupling means and the buffer.

15 4. The combination with a locomotive main frame, of a tender frame, means for coupling said frames, a movable buffer member having oppositely disposed convexed and concaved wear faces formed thereon, a convexed surface formed on one of the frames and adapted to abut against the concaved wear face of the buffer, a movable spring cap, a concaved surface formed thereon and adapted to abut against the convexed wear 20 face of the buffer, and a spring interposed between said cap and one of the frames.

25 5. The combination with a locomotive main frame, of a tender frame, means for coupling said frames, a convexed surface formed on one of the frames, a spherically concaved member supported by the other frame, and a movable buffer member having a spherical wear face formed thereon and adapted to abut against the spherically concaved member, said buffer member also having a concaved wear face formed thereon and oppositely disposed to said spherical wear face and adapted to abut against said convexed surface.

30 40 6. The combination with a locomotive main frame, of a tender frame, coupling draw pins fastened on said frames, a draw bar longitudinally disposed between the frames and coupled thereto by the draw bar pins, a vertical convexed surface formed on one of the frames and concentrically disposed with respect to the axis of the corresponding draw bar pin, a concaved surface formed on the other frame and disposed concentrically with respect to the corresponding draw bar pin, a movable buffer member, interposed between, and abutting against, said surfaces, a convex wear face adapted to abut against the concaved surface, and a concaved wear face to abut against said convexed surface, said wear faces being oppositely disposed and formed on the buffer member.

35 45 50 55 60 65 7. The combination, with a locomotive main frame, of a tender frame, oppositely disposed convexed and concaved buffer surfaces formed on said frames, an interposed movable buffer member having correspondingly formed wear faces abutting against said buffer surfaces, draw bar pins fitted in the locomotive and tender frames, a service draw

bar coupled to said pins, and a safety draw bar independently coupled to said pins, said safety draw bar having a predetermined degree of longitudinal freedom on the pins, whereby it is exempted from stress until the 70 service draw bar is unduly elongated by excessive strain or wear.

8. The combination with a locomotive main frame, of a tender frame, oppositely disposed buffer surfaces formed on the frames, 75 an interposed movable buffer member having wear faces formed thereon and abutting against said surfaces, draw bar pins, a service draw bar coupled thereby to the frames a safety draw bar having a greater length 80 than the service bar, said draw bar pins being fastened on their respective frames and projecting through opposite ends of the draw bars in a manner to engage the service bar and apply stress thereto, so as to keep 85 the safety draw bar free from stress until there is a predetermined elongation of the service draw bar.

9. The combination with a locomotive main frame, of a tender frame, coupling 90 draw bar pins fastened on said frames, a draw bar disposed between the frames and pivotally coupled thereto by the draw pins, a convexed surface supported on one frame, a concaved surface supported on the other 95 frame, a movable cellular buffer member interposed between, and abutting against, said surfaces and adapted to embrace, and swing horizontally or move laterally with, the draw bar as it pivotally swings on one 100 of the draw pins, to compensate for any relative horizontal movement between the frames as the locomotive passes over curves, or uneven track.

10. The combination with a locomotive 105 main frame, of a tender frame, coupling draw bar pins fastened on said frames, a draw bar disposed between the frames and pivotally coupled thereto by the draw pins, a convexed surface supported on one frame, 110 a concaved surface supported on the other frame, a movable buffer member interposed between, and abutting against said surfaces, a convexed wear face and draw bar pin slot formed at the rear end of the buffer, the slot 115 being concentrically disposed with respect to the wear face and adapted to embrace the corresponding draw bar pin, and a concaved wear face formed on the front end of the buffer and adapted to abut against said convexed surface formed on the frame and concentrically disposed with respect to the corresponding draw bar pin.

11. The combination with two railway vehicles to be connected, of a draw bar pivotally connected at its ends thereto, and a supplemental safety connection also pivotally connected at its ends thereto, with the axis of its pivotal connection to each vehicle substantially coincident with the axis of the 120 125 130

5 pivotal connection of the draw bar to said vehicle, the parts being so relatively arranged that the draw bar connection, so long as it is operative, forms the load transmitting connection between said vehicles.

12. The combination with two railway vehicles to be connected, of a draw bar, draw bar pins pivotally connecting the ends of the draw bar to said vehicles, and a supplemental safety connection connected by said draw bar pins to said vehicles with provision for lost motion whereby said draw bar forms the load transmitting connection between said vehicles so long as the latter are 10 operatively connected by said draw bar.

13. In a locomotive and tender connection, the combination of two coupling pins, socketed, respectively, on the locomotive and tender; a service draw bar, coupling said pins; 20 a safety draw bar, also coupling said pins and having a predetermined degree of longitudinal freedom thereon; and a buffer member interposed between, and bearing on, the locomotive and tender.

14. The combination with two railway vehicles to be connected, each provided with a vertical draw bar pin and upper, intermediate and lower apertured parts through which said pin passes and which provides 30 bearings for upper, lower and intermediate portions of the pin, and a pair of coupling parts each pivotally connected at its opposite ends to the two draw bar pins, one of said coupling parts being received between the upper and intermediate apertured parts and the other between the intermediate and lower apertured parts of each vehicle, the lower apertured part of each vehicle having provisions engaging the lower portion of the 40 corresponding draw bar pin to prevent downward movement of the pin.

15. The combination with an engine having a foot plate provided with a drawbar pocket and beneath the drawbar pocket with 45 a pocket for receiving the end of a safety bar and formed with alined passages through the walls of said pockets for a drawbar pin, and a tender having a drawbar pocket member formed with a drawbar

pocket proper and beneath the latter with 50 a pocket to receive the end of a safety bar, and formed also with alined passages through the walls of said pockets for a drawbar pin, of a drawbar having its ends received in the drawbar pockets of said foot 55 plate and member and having apertures in its ends to receive the drawbar pins, and a safety bar having its ends received in the lower pockets of said foot plate and drawbar pocket member, and having apertures in its 60 ends to receive said drawbar pins, and drawbar pins mounted in said passages and passing through said apertures, the apertures in said bars being so relatively arranged as to prevent the safety bar from being put under 65 tension so long as the drawbar forms an operative connection between the engine and tender.

16. The combination with an engine having a foot plate provided with a drawbar 70 pocket and beneath the drawbar pocket with a pocket for receiving the end of a safety bar and formed with alined passages through the walls of said pockets for a drawbar pin, and a tender having a drawbar 75 pocket member formed with a drawbar pocket proper and beneath the latter with a pocket to receive the end of a safety bar, and formed also with alined passages through the walls of said pockets for a 80 drawbar pin, of a drawbar having its ends received in the drawbar pockets of said foot plate and member and having apertures in its ends to receive the drawbar pins, and a safety bar having its ends received in the 85 lower pockets of said foot plate and drawbar pocket member, and having apertures in its ends to receive said drawbar pins, and drawbar pins mounted in said passages and passing through said apertures, and means 90 for retaining the lower portions of the drawbar pins in case of rupture of upper portions of said pins.
